CHARLES H. HELLING, OF OAKLAND, CALIFORNIA, ASSIGNOR OF ONE-HALF TO
GEORGE C. LESTER, OF OAKLAND, CALIFORNIA.

SWITCH ATTACHMENT FOR ELECTRIC IRONS.

1,342,905.

Specification of Letters Patent.

Patented June 8, 1920.

Application filed April 3, 1919. Serial No. 287,101.

To all whom it may concern:

Be it known that I, CHARLES H. HELLING, a citizen of the United States, residing at Oakland, in the county of Alameda and State of California, have invented new and useful Improvements in Switch Attachments for Electric Irons, of which the following is a specification.

This invention relates to an automatic switch attachment for electric irons.

One of the objects of the present invention is to provide a simple, easily operated switch attachment for electric irons which is capable both of automatic and manual operation and in which the switch may be locked in the on-position when the iron is stood on end.

Another object of the invention is to provide a novel connection between the terminals of the heating element employed and the terminals of the switch.

Further objects will hereinafter appear.

The invention is further illustrated by way of example in the accompanying drawings, in which—

Figure 1 is a side elevation of an electric iron partly in section, showing the application of the invention.

Fig. 2 is a side elevation of the iron showing it up-ended with the switch in an open position.

Fig. 3 is a front view of the socket supporting the switch, said view being partly in section.

Fig. 4 is a rear view of the socket.

Fig. 5 is a central and vertical section of the socket.

Fig. 6 is a detailed sectional view of the contact end of the switch lever.

Referring to the drawings in detail, A indicates the body portion of a standard form of electric iron; 2, the base; 3, the handle; and 4, the socket in which the plug 5 is inserted when it is desired to employ the iron. Mounted interior of the body portion of the iron, adjacent the inner face of the base plate 2 is a heating element of suitable construction. This element is not shown in the present instance as it does not form any part of the invention. The terminals of said element are connected with plug terminals such as shown at 6 and 7, see Fig. 5. These plug terminals are mounted within the socket 4 and a circuit through the same is established in a manner hereinafter to

be described. The plug 5 employed consists of a yoke-shaped member 8, which carries an insulating member 9. The cord through which the current is supplied passes through a bushing 10 formed in the upper end of the yoke and the two wires forming the cord are attached to terminals 11 and 12 secured to the insulating member 9 of the plug. The insulating member 9 is loosely mounted within the yoke but is forced tightly down into the socket 4 when inserted as the yoke 8 is forced downwardly until it is permitted to straddle a pair of pins 13, secured one on each side of the socket 4. To permit the lower ends of the yoke to engage said pins, slots 14 are formed. These slots are elongated, as shown in Figs. 1, 2 and 5, and to prevent disengagement of the yoke with relation to the pins 13, head members 15 are provided. The heads of the pins proper may be turned into alignment with the slots 14 when the yoke is applied and then turned crosswise of the slots, as shown in Fig. 2, to prevent accidental removal of the yoke.

Attached to the terminal member 12, secured on the insulating member 9, is a coil spring 16 and similarly attached to a third terminal member indicated at 17 is a coil spring 18. These coil springs are mounted in alignment with the plugs 6 and 7 and surround the same when the plug is inserted. They are also placed under compression as they engage the base portions of the plugs 6 and 7, thereby insuring a perfect contact as the springs do not only engage the base portions of the terminals with considerable pressure but they also engage the sides of the extended portions of the plugs.

For the purpose of making or breaking a circuit through the heating element, I employ a pair of spring contacts 19 and 20. One contact is connected with a terminal 11 while the other contact is connected with the terminal 17. A circuit established between the contacts 19 and 20 permits the current to pass from the terminal member 11 through the contacts 19 and 20, then to pass through the terminals 17, coil 18, and plug 6. The current will here pass through the heating element, then out through the opposite terminal 7, then passes through the coil 16 and terminal 12, thus completing the circuit. For the purpose of making or breaking a circuit between the contacts 19 and 20

and 20, I employ a switch lever 21. This lever is pivotally mounted as at 22, in a plate 23, secured to the front face of the insulating member 9 by means of a screw 24.

5 Formed on the inner end of the lever 21 and adapted to pass between the contacts 19 and 20 is a segment 25. The handle 21 and the segment 25 are constructed of insulating material and will therefore at all times 10 prevent a circuit from being established between the spring contacts 19 and 20. I have, however, provided means for establishing a circuit between said members and inclosing the upper end of the segment 25 with a 15 metal contact piece 26. This member passes between the spring contacts 19 and 20 when the handle 21 is moved into the horizontal dotted line position shown at 21^a, in Fig. 1, and this is only accomplished by manual 20 operation on the part of the operator employing or using the iron. In other words, the circuit through the iron is at all times broken by means of the switch lever 21 unless it is manually raised up against the 25 handle 3 by the operator, which is accomplished by merely grasping the lever 21 in unison with the handle 3 and pulling the lever 21 upwardly until it lies flush with the handle. This position of the lever 21 30 brings the metal contact member 26 in position between the spring contacts 19 and 20 and thus establishes a circuit through the heating element within the iron whenever desired.

35 In actual operation, if the iron is cold and it is desired to heat the same to proper temperature before the iron is to be used, it is only necessary to stand it on end, as shown in Fig. 2 and to pull the lever 21 up against the handle 3 or to the dotted line position shown at 21^a in Figs. 1 and 2. The lever 21 is here automatically locked by means of a weighted latch 26' which is pivotally mounted, as at 27, at the outer 40 end of the lever. This latch engages a keeper plate 28 secured in a longitudinally disposed groove 29 formed on the lower side of the handle 3. This groove also contains a leaf spring 30 which is secured at one end 45 by means of the keeper plate 28 while its opposite end engages the switch lever 21. This spring therefore normally serves the function of depressing the switch lever and consequently breaking the circuit through 50 the plug and the heating element and it will always maintain the switch lever in the depressed position unless it is manually raised by the operator employing the iron or locked by means of the latch 26'. The 55 operation of the switch is therefore, to a certain extent, automatic when ironing; to the extent that whenever the iron is being employed, the operator grasps the lever 21 and the handle 3 in unison, thereby raising the lever 21 to a position where the circuit 60

is closed. The circuit is therefore on as long as the iron is being employed but it is instantly broken the moment the iron is released as the weighted latch 26' will not engage the keeper when the iron is in a 70 horizontal position. The operator can therefore leave the iron whenever desired, without any danger of burning or scorching the clothes or overheating the iron as the circuit through the same is instantly broken 75 the moment the handle 3 is released. The circuit may, however, be maintained, if desired, by placing the iron on end, as shown in Fig. 2, and by locking the switch lever by means of the latch 26'. The weight carried by the latch 26' insures engagement of the latch with the keeper when the iron is up-ended and it also prevents engagement with the keeper when the iron assumes its normal horizontal position. It thereby 80 acts as a safety device which positively prevents overheating of the iron or a constant circuit through the same when it assumes a horizontal position.

An iron equipped with a switch mechanism, such as here shown, has many advantages when compared with ordinary electric irons as it saves, first, by saving current when ironing as the current is automatically turned off when the iron is released; second, accidental fires are prevented for the same reason; third, the iron is more convenient to handle and operate as it is not necessary to pull out the plug if the iron becomes too hot or to re-insert the 90 same if the iron becomes too cold; fourth, by eliminating the necessity of constantly removing or inserting the plug it prevents wearing away of the contacts and the electric cord passing through the same, thus 95 eliminating short circuits and fire dangers resulting therefrom; fifth, the switch lever is always positioned directly under the handle and is only pulled up against the handle when the iron is used or when required; 100 sixth, the switch lever can only be left on at will when the iron is up-ended but in no other position and will automatically release itself if the iron is over-turned or assumes a horizontal position, due to the fact 105 that the weighted latch member 26 will release itself.

The switch mechanism, constructed as here shown, may be attached to any standard form of iron and should therefore prove 110 a great advantage whether it be to the manufacturer or the user as the heating element and the main portions of the iron employed do not require changing and while a more or less specific structure is here shown, I 115 wish it understood that this may be changed; similarly, that the materials and finish of the several parts employed may be such as the judgment and experience of the manufacturer may dictate.

Having thus described my invention, what I claim and desire to secure by Letters Patent is—

1. The combination with a handle of an electric iron, and a switch on the iron, of a lever pivotally mounted in the switch adapted to make or break a circuit through the switch, a spring interposed between the handle and the lever adapted to normally hold the lever in a position where the circuit through the switch is broken, and means for locking the lever with relation to the handle when the circuit through the switch is closed, said means being only operable when the iron is placed on end, and said means adapted to automatically release the lever when the iron is moved into horizontal position. 10
2. The combination with a handle of an electric iron, and a switch on the iron, of a lever pivotally mounted in the switch adapted to make or break a circuit through the switch, a spring interposed between the handle and the lever adapted to normally hold the lever in a position where the circuit through the switch is broken, and a latch for locking the lever with relation to the handle when the circuit through the switch is closed, said latch being only operable when the iron is placed on end, and said latch adapted to automatically release itself when the iron assumes a horizontal position. 20
3. The combination with a handle of an electric iron, and a switch on the iron, of a lever pivotally mounted in the switch adapted to make or break a circuit through the switch, a spring interposed between the handle and the lever adapted to normally hold the lever in a position where the circuit through the switch is broken, a latch pivotally mounted on the outer end of the lever, a keeper in the handle with which the latch is adapted to engage to lock the lever when the switch is in a closed position, said latch being weighted and being only operable to lock the lever when the iron is placed on end, said latch automatically releasing itself when the iron assumes a horizontal position. 30
4. The combination with the handle of an electric iron and a socket mounted at one end thereof, of a plug adapted to be inserted in the socket, a lever pivotally mounted in the plug and adapted to make or break the circuit therethrough, a spring interposed between the handle and the lever, adapted to normally depress the lever to position when the circuit through the plug is broken, and means for locking the lever with relation to the handle so as to close the circuit through the plug. 40
5. The combination with the handle of an electric iron and a socket mounted at one end thereof, of a plug adapted to be inserted in the socket, a lever pivotally mounted in the outer end of the lever, and a keeper in the handle, said latch being weighted and being only operable to lock the lever when the iron is placed on end, said latch adapted to automatically release itself when the iron assumes a horizontal position. 50
6. The combination with an electric iron and the heating element mounted therein, of a socket member mounted on the iron having a pair of terminal members mounted therein, connected with the heating element, a plug member insertible in the socket, adapted to establish a circuit through the heating element, and a switch lever projecting from the plug for making or breaking a circuit therethrough. 60
7. The combination with an electric iron and the heating element mounted therein, of a socket member mounted on the iron having a pair of terminal members mounted therein, connected with the heating element, a plug member insertible in the socket, adapted to establish a circuit through the heating element, a switch lever projecting from the plug for making or breaking a circuit therethrough, and means for locking the switch lever in closed position, said means being only operable when the iron is placed on end and said means adapted to automatically release the lever when the iron assumes a horizontal position. 70
8. The combination with an electric iron and the heating element mounted therein, of a socket member mounted on the iron having a pair of terminal members mounted therein, connected with the heating element, a plug member insertible in the socket, adapted to establish a circuit through the heating element, a switch lever pivotally attached to the plug, and means on said lever for making or breaking the circuit through the plug. 80
9. The combination with an electric iron and the heating element mounted therein, of a socket member mounted on the iron having a pair of terminal members mounted therein, connected with the heating element, a plug member insertible in the socket, adapted to establish a circuit through the heating element, a switch lever pivotally attached to the plug, means carried by said lever for making or breaking a circuit through the plug, said lever adapted to be manually operated to close the circuit and automatically actuated when released, to break the circuit. 90

10. The combination with an electric iron and the heating element mounted therein, of a socket member mounted on the iron having a pair of terminal members mounted therein, connected with the heating element, a plug member insertible in the socket, adapted to establish a circuit through the heating element, a switch lever pivotally attached to the plug, means carried by said lever for making or breaking a circuit through the plug, said lever adapted to be manually operated to close the circuit and automatically actuated when released, to break the circuit, and means for locking the lever 10 when the circuit is closed, said means being only operable when the iron is placed on end and said means adapted to automatically release the lever and break the circuit if the iron assumes a horizontal position.
- 15 11. The combination with an electric iron and the heating element mounted therein, of a socket member mounted on the iron having a pair of terminal members mounted therein, connected with the heating element, a plug member insertible in the socket adapted to establish a circuit through the heating element, a switch lever pivotally attached to the plug, means on said lever for making or breaking the circuit through the plug, a handle on the iron, a spring secured to said handle, engageable with the switch lever to normally hold it in a position such that the circuit will be broken and necessitating raising of the switch lever up under 20 the handle to insure a circuit through the iron, a keeper in the handle and a weighted latch pivotally mounted in the outer end of the switch lever engageable with said keeper to lock the lever with relation to the handle, 25 said latch being only operable when the iron is standing on end and adapted to automatically release the lever if the iron is moved to horizontal position.
- 20 12. The combination with an electric iron and the heating element mounted therein, of a socket member mounted on the iron having a pair of terminal members mounted therein, connected with the heating element, a plug member insertible in the socket, adapted to establish a circuit through the heating element, a switch lever pivotally attached to the plug, means on said lever for making or breaking the circuit through the plug, a handle on the iron, a spring secured to said handle, engageable with the switch lever to normally hold it in a position such that the circuit will be broken and necessitating rais-

ing of the switch lever up under the handle to insure a circuit through the iron.

35

12. The combination with an electric iron and the heating element mounted therein, of a socket member mounted on the iron having a pair of terminal members mounted therein, connected with the heating element, a plug member insertible in the socket, adapted to establish a circuit through the heating element, a switch lever pivotally attached to the plug, means on said lever for making or breaking the circuit through the 40 plug, a handle on the iron, a spring secured to said handle, engageable with the switch lever to normally hold it in a position such that the circuit will be broken and necessitating raising of the switch lever up under 45 the handle to insure a circuit through the iron, a keeper in the handle and a weighted latch pivotally mounted in the outer end of the switch lever engageable with said keeper to lock the lever with relation to the handle, 50 said latch being only operable when the iron is standing on end and adapted to automatically release the lever if the iron is moved to horizontal position.

In testimony whereof I have hereunto set my hand in the presence of a subscribing witness.

CHARLES H. HELLING.

Witness:

JOHN H. HERRING.
